PRECISION LAMP ADAPTER

Eugene W. Beggs, Glen Ridge, N. J., assignor to
Westinghouse Lamp Company, a corporation
of Pennsylvania

Application June 27, 1933, Serial No. 677,810

4 Claims. (Cl. 176—32)

This invention relates to an electric incandescent lamp and socket and relates particularly to an adapter for holding a projection lamp in a socket.

5 The commercial type of projection lamp extensively used is constructed with projections in the form of fins or pins which extend from the cylindrical wall of what may be termed a secondary or auxiliary base. In practice a lamp is
10 made with the usual type of base which is positioned with the usual commercial accuracy. Another base having fins or pins projecting therefrom is applied to the first base and secured by solder in such position that the fins are a definite
15 distance from the light source. These pins or fins serve in conjunction with a socket to position the light source in a predetermined position with respect to a reflector when the lamp is in a projection unit. The use of fins or pins positioned as
20 above described is well known in the lamp art and the present invention aims to utilize such type of lamp in projection equipment designed for holding a lamp having a different structure. For example, Patent 1,675,554 to Howell, issued July,
25 1928 discloses a form of projection lamp housing which requires a lamp having a special base construction. The base of a lamp to be used in the unit disclosed in this patent includes an annulus which is soldered on a screw base a definite dis-
30 tance from the light source. The attachment of an annulus to a base necessitates a somewhat laborious as well as a costly operation as compared to the use of an auxiliary base on standard projection lamps in wide commercial use.

35 The use of housings, such as shown in the above mentioned patent, have, however, created a demand for projection lamps for use therein but, obviously, by reason of the peculiar form of the annulus employed, the commercial type of
40 projection lamp, such as the one above mentioned, having fins, cannot be used in the sockets of housings of constructions such as that shown in the patent above mentioned.

45 It is an object of the present invention to provide an adapter whereby a projection lamp of the fin type may be used in sockets constructed to receive a different type of lamp.

50 Another object of the invention is to provide a simple and effective adapter which may be quickly and conveniently applied to a lamp base.

55 Another object of the invention is to provide an adapter so constructed and arranged as to hold a lamp in a socket by engagement with fins projecting radially from the lamp base.

55 Other objects and advantages of the inven-

tion will be more clearly understood by reference to the following description together with the accompanying drawing in which

Fig. 1 is a side elevational view of a lamp housing or chamber shown in cross section with a 5 projection lamp held therein by an adapter constructed in accordance with the present invention;

Fig. 2 is a view taken on line II—II in Fig. 1 with the lamp removed; 10

Fig. 3 is a perspective view of an adapter for holding a lamp in the socket;

Fig. 4 is a perspective fragmentary view of a projection lamp showing a base having extensions or fins secured to the base. 15

Fig. 5 is a fragmentary detailed view of a portion of the adapter showing a lamp base fin disposed in position and held by a resilient member.

Although the present form of adapter may find use in other forms of sockets or housings, it 20 is particularly adapted for use in a light unit, as shown in Fig. 1, comprising a cylindrical casing 10 which constitutes the main portion of a lamp chamber. Secured to the lower end of the casing is a socket 11 which socket constitutes the 25 lower portion or bottom of the lamp chamber. The socket may comprise a tubular body portion 12 made of any suitable insulative material. The interior of the tubular casing communicates with the lamp chamber. The body portion 12 is pro- 30 vided with an annular contact member or ring 13 which is imbedded in and extends from the interior surface of the tubular body 12. This annular contact is provided with a foot piece 14 to which may be secured an electrical conductor 35 15. The foot piece 14 of the contact 13 is disposed in a recess 16 in the outer wall of the tubular body 12.

Another recess 17 is provided in the outer wall of the body 12 to accommodate a foot piece 18 40 which is integral with and extends from a metallic collar 19. The outer surface of the collar 19 fits a counter-bore portion of the tubular body 12.

A conductor 21 is suitably connected with the foot piece 18 and a cover plate 22, provided with 45 apertures through which the conductors 15 and 21 extend, is secured to the tubular body 12. The metallic collar serves as a conductor member and its interior surface is threaded to receive an externally threaded cup-shaped member 23 which 50 is secured to a disc 24 of insulative material provided with a projection or finger piece 25 which constitutes a closure 25' for the lower end of the tubular body through which a lamp may be inserted or removed. The cup-shaped member 23 55

is provided with a spring finger 26 electrically connected with the cup-shaped member.

For the purpose of positioning a lamp in the above described socket in a definite position, the 5 annular contact 13 is provided with a notch 27 to receive means fixed on the lamp to prevent its relative rotary movement in the socket.

The present invention aims to provide an adapter which makes it possible to accurately 10 support a projection lamp having a base with fins, such as shown in Fig. 4. This lamp may comprise a bulb 28 having mounted therein the usual filamentary light source 29 supported from a press 31. The bulb is provided with a base 32 15 which base is applied to the bulb with the usual manufacturing accuracy. This base is then inserted into an outer or secondary base 33 having extensions or fins 34. While the secondary base is free to move relative to the primary base, it is 20 adjusted until the fins 34 are a predetermined distance from the center of the light source 29. When so adjusted the secondary base is secured by solder 35 to the primary base.

A projection lamp so constructed is then ready 25 to be inserted into fixtures arranged to engage the fins. When it is desirable to use this type of lamp in a base, such as shown in Fig. 1, however, an adapter 36, as more clearly shown in Fig. 3, is employed. This adapter is of tubular form to 30 slidably fit the cylindrical secondary base 33 and is provided with an annulus or flange 37 externally extending from one edge thereof. This flange is provided with a seat 38 so proportioned as to receive and accommodate the fins 34. Above 35 the seat for the fins and at opposite sides of the upper edge of the adapter are disposed arcuate shaped retainer arms 39. These arms are disposed in such spaced relation to the seat 38 as to provide slots 41.

40 Each of the arms 39 extend only part way around the edge of the seat so that lamps may be first positioned with the fins on the surface 42 and by rotating the lamp in the direction of the arrow X, the fins may be moved beneath the arms.

45 In the lamp housing, as shown in Fig. 1, the annular contact 13 is positioned a definite distance from a point on the casing so that when a lamp is in position the light source will be disposed in a predetermined position with respect to 50 a reflector or lens. The adapter constructed in accordance with my invention is so constructed that the normal upper surface of the flange 37 engages the under surface of the contact 13. The arms 39, which extend above the seat 42, are 55 so arranged that their lower surfaces are a given distance from the focal point in the housing and when the upper surfaces of the fins 34 engage the lower surfaces of the arms 39 the light source 29 will be properly disposed, for the effective projection of a beam of light. As above mentioned, the fins are positioned on the base a definite and pre-determined distance from a point in the filament 29. When a lamp having by adapter applied thereto is disposed in a housing the tension mem- 60 ber 26 serves to press the lamp upwardly and maintain the fins in their proper contact relation with the arms 39. In some housings the tension members may not be of sufficient strength to hold 65 the fins and arms in the desired contact relation in which case the adapter may, as shown in Fig. 5, be provided with a spring member 40 which serves to press the fins against the arms 39. The members may be formed with inclined portions 70 40' which, in conjunction with inclined surfaces 75

40" on the arms, facilitate the movement of the fins beneath the arms.

It will be noted that the fins 39 on the base are of different lengths and the spaces between the fixed ends and the free ends of the arms 39 are 5 so proportioned as to receive these fins. This makes it impossible to place a lamp in the adapter except with the filament in a definite position determined by the position of the fins.

For the purpose of positioning a lamp having 10 the adapter applied thereto in a predetermined position in the socket, the adapter is provided with a lug 43 proportioned to enter the notch 21. As shown in Fig. 1, a lamp, with an adapter thereon, may be inserted through the bottom of the 15 tubular body 12 by first removing the closure 25'. When a lamp is in position the annulus 37 will engage the contact ring 13 and when the lower end of the tubular body is closed the resilient member 26 will engage the bottom contact on the 20 lamp and hold the annulus in firm engagement with the contact 13. The lug 43, being disposed in the notch 21, prevents relative rotary movement of the lamp.

When a lamp is held in an adapter electrical 25 energy may flow through the conductor 21, through the metallic parts of the socket and into the lamp through the lower bottom contact thereof. The return flow, will, obviously, occur by means of the electrical contact between the base 30 and the adapter which engages the contact ring 13, the latter being electrically connected with the conductor 15.

It will be evident that, by reason of the present 35 invention, a lamp provided with a secondary base, having extensions or fins thereon, may be easily and quickly provided with an adapter making it possible to use this type of lamp in sockets where heretofore it was necessary to provide a lamp with a special form of base. The adapter, as constructed in accordance with the present invention, 40 is of simple design and may be readily cast or turned from a single piece of metal making the adapter of relatively low cost and of considerable advantage to the users of sockets especially designed for special forms of lamps.

Although a preferred embodiment of the invention is shown and described herein, it is to be understood that modifications may be made therein without departing from the spirit and scope of 50 the invention as set forth in the appended claims.

What is claimed is:

1. In combination with an incandescent electric lamp base having a flange extending therefrom, an adapter, comprising, a tubular member having an inside diameter so proportioned as to slidably fit the outer surface of the base, a contact member extending from the outer surface of said tubular member to engage a contact in a socket, and an arcuate arm spaced from an edge of said tubular member for holding said flange of said lamp base relative to said tubular member.

2. In combination with an incandescent electric lamp base having a laterally extending fin, an adapter comprising, a tubular member to receive 65 said base with the fin thereof adjacent to one edge of said member, an arm extending above and along said edge to hold said fin in spaced relation to said edge and a lateral projection extending from the exterior surface of said tubular member.

3. In combination with an incandescent electric lamp base having a laterally extending flange, an adapter comprising a tubular body to receive a base, a seat for said flange at one edge of said body, an arm above and spaced from said seat and 75

resilient means between said arm and seat for retaining said flange in contact with said arm.

5. In combination with an incandescent electric lamp base having laterally projecting fins on the base thereof, an adapter comprising a tubular body to receive said base, said body having lateral

slots open at opposite ends adjacent to one edge thereof to receive said fins upon a rotation of said lamp when the base portion is disposed in said tubular body and an annular contact member extending from the exterior surface of said body.

EUGENE W. BEGGS.
